BRACELET FOR OPENING HAIRPINS

Alexander Gonzales, Jr., 358 W. Lomita, Apt. 3,
Glendale, Calif. 91204

Filed Apr. 7, 1969, Ser. No. 16,595

Term of patent 14 years

Int. Cl. D3—99

U.S. Cl. D86—10

FIG. 1

FIG. 2

FIG. 3

FIG. 5

FIG. 4

FIG. 6

FIG. 7

FIG. 1 is a top view of a bracket for opening hairpins showing my design;

FIG. 2 is a side elevational view of FIG. 1;

FIG. 3 is a left end elevational view of FIG. 2;

FIG. 4 is a right end elevational view of FIG. 2;

FIG. 5 is a sectional view taken along line 5—5 of FIG. 2;

FIG. 6 is a side perspective view of the bracket for opening hairpins; and

FIG. 7 is a left end perspective view thereof.

I claim:

The ornamental design for a bracelet for opening hairpins, as shown.
